UNITED STATES PATENT OFFICE.

FREDK. BAARE AND JULIUS G. GARELLY, OF NEW YORK, N. Y., ASSIGNEES TO HORACE H. DAY, OF SAME PLACE.

MANUFACTURING CORRUGATED FABRICS.

Specification of Letters Patent No. 24,691, dated July 5, 1859.

To all whom it may concern:

Be it known that we, FREDERICK BAARE and JULIUS GROSS GARELLY, both of the city, county, and State of New York, have invented certain new and useful Improvements in Corrugated Fabrics; and we do hereby declare that the following is a full, clear, and exact description of our said invention, reference being had to the accompanying drawings, in which—

Figure 1 represents a face view of a strip of our fabric; Fig. 2. is a view of the face or right side of a piece of the fabric prior to corrugation; Fig. 3. is a view of a portion of Fig. 2. upon an enlarged scale and reversed so as to exhibit the wrong side of the fabric; Figs. 4 and 5. are views of strips of the fabric having more than two series of corrugations; Figs. 6 and 7. are views of these fabrics extended to show the division lines of the different series of corrugations; Fig. 8 is a view of the wrong side of a sample of the fabric in an extended state; and Figs. 9 and 10 are views of a sample of the fabric having a single contractile strand.

Our invention consists mainly in a corrugated fabric (that is a fabric in which the material forms a series of waves composed of consecutive ridges and furrows) having two or more parallel series of corrugations combined or arranged in such manner with respect to each other that the ridges of each series are opposite the depressed portions of the adjacent series, so that the waves of the adjacent series alternate in the direction in which the series extend. Several examples of this fabric are represented in the annexed drawing at Figs. 1, 4, 5, and 9, which, however differing in other respects, all agree in the peculiarity above mentioned. Thus, the samples represented at Figs. 1 and 9 consist of two series of corrugations, A, and B, which extend parallel and adjacent to each other in the direction of the length of the fabric; the ridges c. c. c. of the series A, alternating with those, i, i, i, of the series B; and the ridges of each series gradually vanishing at the division line where the two series meet. In the example represented at Fig. 4, there are three series of corrugations, each of which bears the same relation to the series adjacent thereto as the series of

the sample represented at Fig. 1 bear to each other. In the sample represented at Fig. 5 there are four series, the corrugations of each of which alternate with those of the adjacent series. In the figures thus represented, which represent samples of our fabric of the most perfect form in which we have thus far manufactured it, the adjacent ends of the corrugations of adjacent series lap past each other, so that, when the fabric is dyed of a bright color, the corrugations present an appearance similar to that presented by the petals of the dahlia, whence we name the improved corrugated fabric when formed of silk, "Rubans dahlia" or "dahlia ribbons;" when formed of this material it constitutes a beautiful trimming for ladies' dresses.

Our improved corrugated fabric may be formed in various ways, but we prefer to manufacture it by weaving a textile material (silk for example) in connection with strands of an elastic material (such for example as india rubber) in an extended state, in such manner that when contraction takes place in the elastic material after the weaving is completed, the compound fabric corrugates itself in the manner exhibited in the finished fabric as shown in the drawing; and we insure a uniformity in size of the overlapping extremities of the corrugations of adjacent series by rendering the fabric more sleazy at the division line between the two in the process of weaving. Thus, in the example represented at Figs. 1, 2, and 3, silk warp and filling are interwoven in a ribbon loom with each other and with two strands of rubber a and e, in an extended state, in such manner that the rubber strands are partially interwoven with the silk filling, and are partially left free therefrom, the manipulation of the leaves of heddles of the loom being so regulated, in the manner familiar to weavers, that the interwoven portions b of one rubber strand, are opposite the bare portions d of the adjacent rubber strand, also that the fabric is loosely tweedled in the direction of the diagonal lines s, r, which connect the interwoven portions of one rubber strand with the interwoven portions of the adjacent strand. When this fabric thus produced is removed from the

- loom and the strands of rubber contract, the compound fabric is gathered up by the contraction into two series of waves whose corrugations are controlled by the rubber strands; and, as these strands are interwoven at alternate parts of the fabric, the corrugations of the fabric are caused to arrange themselves in two series whose members alternate with each other as shown at Fig. 1.
- 10 In the process of corrugation, the division lines or folds of the fabric between the two series of corrugations naturally follow the lines *s*, *r*, because the fabric is more sleazy and less stiff at these lines than elsewhere,
- 15 and the sleaziest portion naturally bends most readily.
- In manufacturing the samples represented at Figs. 4 and 6, two pairs of rubber strands are used, and in manufacturing those represented at Figs. 5 and 7 five single strands are used. If any one series of corrugations is of considerable breadth in proportion to the width of the separate corrugations of which it is composed, it is expedient to introduce one or more supplementary rubber strands at suitable distances apart, to insure uniformity in each wave throughout its entire length; in this case, all the strands appertaining to one series of waves must be interwoven with the parts of the textile material which constitute the depressions of the corrugations, and left detached from those parts which constitute the ridges of the corrugations.
- 35 When the corrugations are very protuberant and gradually vanish into each other at the division line between the two series, it is expedient to introduce a series of strands of rubber between the two extreme lateral bounds of the division line as shown in the view of a reverse side or wrong side of such a specimen previous to contraction, represented at Fig. 8. When on the other hand the corrugations are small, and the fabric has but two series, as shown at Fig. 9, the contraction may be produced by means of a single strand of rubber, as shown at Fig. 10.
- After the fabric is corrugated it may have its appearance varied by pressing down the corrugations into overlapping folds or plaits, but this mode of finishing does not change the fabric to such an extent as to make it no longer embody our invention, as the corrugations are only flattened, and as they still are combined in such manner that the corrugations of adjacent series alternate.
- The rubber strands, if composed of vulcanized rubber or similar material stretched previously to weaving, and maintained in an extended state during weaving, will contract of themselves when they are liberated from the means by which they are maintained in an extended state during the weaving. If, however, the strands be formed of

native rubber or other similar material that 65 may be caused to assume an inelastic condition after being extended, it is necessary to apply heat after the fabric is woven to cause the contraction. The strands thus partially interwoven and partly left bare constitute 70 contractile strands upon which the waves are gathered up, and they can be replaced by strands of inelastic material upon which the waves may be gathered up by drawing the strands after the fabric is woven. In this 75 case however the fabric is not so perfect, as it is practically inelastic.

Having thus described our new fabric and a method of manufacturing the same which we have essayed with success, we deem it 80 proper to state that we do not limit our invention to any peculiarity in the method of manufacture, nor to any particular color or combination of colors in the article, nor to any peculiar material nor to any specific 85 number of contractile strands, as we have no doubt that these may be varied to a very great extent.

We also deem it proper to state that we are aware that ribbons have been so woven 90 upon inelastic contractile strands that the material can be gathered up into plaits by drawing the strands; but in this case the fabric consists either of but one series of plaits, or of two or more series dividing at 95 the contractile strands, but so combined in the fabric that the protuberant portions of one series are in line with the protuberant portions of the adjacent series (instead of alternating as in our fabric), so as to constitute in fact but one series flattened at certain parts of its breadth.

We are also aware that contractile strands of rubber either native or vulcanized, have been used to effect the corrugation of a textile material as is seen in what are called elastic shirred goods, either woven or cemented; but in these cases the parallel strands of rubber are not so interwoven or otherwise combined with the fabric as to be 110 alternately detached therefrom and connected therewith at alternating parts of their length, as they are when used in our fabric; nor are they so combined with the fabric that, when the rubber contracts, the compound fabric gathers up into two or more 115 parallel series of corrugations whose members alternate.

Therefore, what we claim as our invention and desire to secure by Letters Patent 120 is—

1. The combination of two or more parallel series of corrugations in the same fabric in such manner that the ridges of the adjacent series alternate.

2. We also claim combining rubber strands (one or more) with a textile material, in such manner that, when the rubber con-

tracts, the compound fabric gathers up into two or more parallel series of corrugations, whose members alternate.

3. We also claim combining rubber strands with a textile material in such manner that the strands are alternately secured to the fabric and left free therefrom at alternating parts of their length, so that the secured part of one rubber strand corresponds with the free part of an adjacent one.

4. We also claim forming the fabric sleazy at the division lines between the cor-

rugations of adjacent series, so as to insure uniformity in the form of the adjacent extremities of the corrugations.
